United States Patent Office.

JAMES W. NATHAN, OF CHICAGO, ILLINOIS.

Letters Patent No. 93,114, dated July 27, 1869.

IMPROVEMENT IN SKATES.

The Schedule referred to in these Letters Patent and making part of the same.

To all whom it may concern:

Be it known that I, JAMES W. NATHAN, of Chicago, Cook county, and State of Illinois, have invented a new and improved Skate; and I do hereby declare that the following is a full and exact description thereof, reference being had to the accompanying drawings, and to the letters of reference marked thereon, which form a part of this specification.

Figure 1 represents a rear-end view of my improved skate; and

Figure 2 represents a side view of the same.

The nature of my invention consists in providing a skate with a loose heel-piece, loose only so far as vertical and rocking motions are concerned. I fasten the skate to the foot in any of the modes now in use.

The object of the loose heel-piece E is to allow the feet of the skater to move with natural freedom while skating, at the same time keeping perfect control of the rear end of the skate, without the necessity of

binding the foot so tight as to retard the circulation of the blood, thus obviating a very great evil experienced by all skaters while using the common skate, strapped in the usual manner.

The loose piece E is placed astride of the runner A, as shown in fig. 1; and pins, D and B, are made fast in the loose piece E, and passed through slots C and C' in the runner A, as shown.

Having thus fully described my invention,

What I claim as new, and desire to secure by Letters Patent of the United States, is—

The movable heel-plate E, having lugs F F and pins B D, in combination with the slots C C' in the runner A, as and for the purpose set forth.

JAMES W. NATHAN.
